LIQUID DISPENSER FOR A FLOOR TREATING MACHINE

Olin C. Hershberger and Chester B. Derr, % Astro Incorporated, Box 277, Thompson, Conn.

Filed May 15, 1964, Ser. No. 80,042

Term of patent 14 years

(Cl. D9—2)

FIG. 1

FIG. 2

FIG. 3

FIG. 1 is a view in front elevation of a liquid dispenser for a floor treating machine, showing our new design; FIG. 2 is a view in side elevation thereof; FIG. 3 is a view in rear elevation thereof; FIG. 4 is a bottom plan view thereof; and FIG. 5 is a top plan view thereof.

The side not shown has substantially the same appearance as the side shown.

We claim:

The ornamental design for a liquid dispenser for a floor treating machine, as shown and described.
